Primary Examiner — Mary Ann Calabrese*Assistant Examiner* — Katelin G Kloberg(74) *Attorney, Agent, or Firm* — Karish & Bjorgum, PC(57) **CLAIM**

The ornamental design for spring crate fastener, as shown and described.

DESCRIPTION

FIG. 1 is a front right perspective view of a spring crate fastener, showing my new design;

FIG. 2 is a front view of the spring crate fastener of FIG. 1.

FIG. 3 is a rearview of the spring crate fastener of FIG. 1.

FIG. 4 is a right side view of the spring crate fastener of FIG. 1, with the left side view being a mirror image of FIG. 4.

FIG. 5 is a top view of the spring crate fastener of FIG. 1; and,

FIG. 6 is a bottom view of the spring crate fastener of FIG. 2.

The features shown in dashed lines form no part of the design and are not claimed.

1 Claim, 2 Drawing Sheets
